UNITED STATES PATENT OFFICE.

REED ADAMS, OF DETROIT, MICHIGAN.

METHOD AND APPARATUS FOR AFFIXING STAMPS ON MAIL MATTER.

Application filed August 21, 1924. Serial No. 733,332.

My invention relates to a method and apparatus for affixing precancelled stamps on matter to be mailed.

It is usual to send out mailing folders with their edges temporarily fastened together, as for instance, by a clip, or by a precancelled stamp placed by hand so as to extend over the edges and adhere to opposite surfaces of the folders. A special object of my invention is to apply a stamp to such folders so as to join the free edges of the same so as to secure neatness, speed, and accuracy and to employ in part existing apparatus.

15 In the accompanying drawings:—

Figure 1 is a side elevation of an apparatus embodying my invention and used in the performance thereof.

Fig. 2 is an end view to a larger scale looking from the right of Fig. 1.

Fig. 3 is a plan view of the same, a portion being broken away.

Fig. 4 is a section on the line IV, IV, Fig. 3, looking in the direction of the arrows.

25 Fig. 5 is a perspective view of a folder, the stamp being partly fixed in place.

Fig. 6 is an inverted plan view of a clutch of a stamp-affixing machine altered to adapt the machine for use in my invention.

30 Fig. 7 is a similar view of the unaltered clutch.

In Figures 6 and 7, 2 is the adjusting plate, 3 the flat nut for adjusting screw, 4 35 clutch rollers, 5 clutch ring carrying rollers and 6 is the clutch block.

40 *a*, is a known machine for affixing stamps to envelopes or other mailing matter. I have shown for illustration the apparatus known as the mail-o-meter.

I adapt this to my purpose by lowering the platform, or track, along which the folder passes to an extent that brings half the stamp above the upper edge of such folder, 45 as shown in Fig. 5, in which *b* is a folder with the stamp *c* affixed to the upper edge thereof and extending above said edge.

I also arrange the clutch as shown in Fig. 6 and extend the arcuate slots as there shown 50 so as to secure a greater range of adjustment for positioning the stamp. I then adjust the clutch as shown in Fig. 6, so that the stamp shall be placed midway between the end edges of the mailing matter, as shown in Fig. 5.

Fig. 7 shows the clutch as it is arranged for use with ordinary mail matter so that the changes shown in Fig. 6 will be readily seen by those familiar with the art.

d, is the stacker plate and *e* is a cam acting through an aperture in the plate *d* to act upon the envelopes, or mail matter that has been delivered from the machine *a*. This is called the "stacker rubber."

*a*³, (Figs. 3 and 4), is a narrow groove 65 in which the lower edge of the folder, or mail matter, slides when it is delivered in a vertical position from the machine in front of the stacker plate *d* in position to be acted on by the cam, or rubber, *e*.

At the place of delivery of the machine *a*, at the stacker plate *d*, I put a laterally extending set of rolls, *f*, *f*, *f*, (Fig. 4), with a carrier band, *f*², extending around said rolls.

*f*², is a roll located above the middle one of the first mentioned rolls and carried in a movable bearing at each end of a transversely extending yoke, *f*^{3a}, carried by pivoted levers, *f*^{3b}, which levers are pivoted to the upper end of a second pivoted lever, *f*^{3d}. *f*^{3c}, is a spring acting to yieldingly urge the arm, *f*^{3b}, in a direction to carry the roller, *f*², toward the roller, *f*, below the same.

*f*⁴, is a roller above the outer end roller, *f*⁵, of the first mentioned series of rollers. This is also pressed yieldingly downward. *f*⁵ and *f*⁶, are delivery rolls.

The rolls are actuated through a series of intermeshing tooth gears, *f*⁷, (Fig. 2), with 90 the intermediate adjustable tooth gear, *f*⁸. *h*, is a frame work in which the above described rollers bear which is supported on adjustable arms, *h*², *h*², above the frame work, *h*³.

95 *g*, is an electric motor and *j* is a centrifugal fan, or blower. *g*⁴, is a belt wheel upon the shafts of one of the gearings supported in the frame, *h*, through which the various rollers are actuated. *g*², is a belt through 100 which the fan blade is actuated by the motor, *g*, and *g*³ is a belt by which said fan turns the wheel, *g*⁴.

*h*² is a pipe through which the fan drives a current of air and *h*² is a horizontal portion of the pipe, *h*, extending parallel and just above the edge of the stacker plate, *d*. *h*³ is an aperture in the wall of the horizontally extending portion, *h*², of the pipe *h*, so located and constructed as to throw a jet of 110

air slantingly downward and outward from the stacker plate d , as indicated by the arrows in Fig. 4.

The operation of the above described apparatus is as follows:—

The folders are fed to the machine a at the left, as shown in Fig. 1, on the platform, or track, a^2 , in the usual way and in a vertical position with unattached edges upward. Said machine being adjusted as above described, in the operation of the machine a stamp is moistened and affixed to the folder as shown in Fig. 5, about half of the stamp extending above the upper edge a^3 of the folder and midway between the two end edges thereof. The folder is then delivered with its lower edge in the groove a^3 , against the inner surface of the stacker plate d , and is acted on by the cam e , to incline it outward, as shown in broken lines in Fig. 4, said groove preventing the lateral movement of its lower edge. This movement of the folder brings it into the jet of air from the aperture k^3 , which jet forces it downward until the protruding portion of the stamp c strikes against the roller f^3 , (Fig. 4), and is bent over thereby and until the lower surface of the folder engages the carrier belt f^2 at the first of the rollers f . Thus the stamp c is bent over and when the folder b comes in contact with the belt f^2 above the first of the rollers f , it is carried along, thereby carrying the forward edge thereof and the stamp c under the roller f^3 , which presses the protruding portion of said stamp upon the then upper edge of the folder, as shown at e^2 , (Fig. 4), so that the stamp adheres to opposite faces of the folder and unites the otherwise free edges. It is then delivered by the rollers f^5 , f^6 .

This action is entirely continuous and automatic, only requiring that the mail matter should be supplied to the machine as above described. The folder is not only stamped, but the otherwise free edges are united, thus forming a compact and convenient piece for mailing.

What I claim is:

1. In combination with a stamp-affixing machine adjusted to affix the stamp to one surface of folder with a portion of said stamp protruding beyond the edge thereof, and to deliver the folder in a vertical position with a stamp at the upper edge thereof, of means for causing said folder to fall laterally turning about its lower edge, means interposed in the line of travel of the protruding portion of the stamp while the folder is falling, adapted to strike against said protruding portion of the stamp and bend it toward another surface of said folder, and means for pressing the turned-over protruding portion of the stamp against said other surface of the folder.

2. In combination with a stamp-affixing machine adjusted to place the stamp upon one surface of a folder so as to partly extend beyond the edge thereof and deliver the same in a vertical position with a stamp at the upper edge of said folder, conveying rollers at the delivery end of said machine adapted to receive the folder and convey it at right angles to its direction of delivery to said machine, means for causing said folder to turn about its lower edge causing the protruding portion of said stamp to strike against an object and bend over towards another surface of said folder and to engage said conveying rollers to be carried therethrough, said rollers being adapted to press the turned-over portion of said stamp upon another surface of said folder.

3. In combination with a stamp-affixing machine adjusted to place the stamp upon a folder so as to partly extend beyond the edge thereof and deliver the same in a vertical position with the stamp at the upper edge of said folder, conveying rollers at the delivery end of said machine adapted to receive the folder, means for producing a jet of air adapted to cause said folder to turn about its lower edge to engage said conveying rollers and means for turning the protruding portion of the stamp over toward another surface of the folder previous to its engagement with said rollers, said rollers being adapted to fix the stamp in its bent-over position.

4. In combination with a stamp-affixing machine adjusted to place the stamp upon a folder so as to partly extend beyond the edge thereof and deliver the same in a vertical position with a stamp at the upper edge of the folder, conveying rollers at the delivery end of said machine adapted to receive said folder, means for turning over the protruding end of said stamp, means for supplying a jet of air adapted to impel said folder toward said rollers to engage the same, and a mechanical means for actuating said folder so that it shall be engaged by said jet of air.

5. In combination with a stamp-affixing machine adjusted to place a stamp upon one surface of the folder with a portion of it protruding above the upper edge thereof, said machine having a delivery groove and delivering said folder with its lower edge in said groove, an actuating device acting upon one surface of said folder to turn it in said groove, means for bending the protruding portion of the stamp over and rollers adapted to receive said folder and to affix the stamp thereon in its bent-over position.

6. The method of affixing stamps to mailing folders so as to join the free edges thereof, consisting in passing said folders through a means for affixing the stamp to one surface of a folder with a portion of

said stamp protruding beyond the edge of the folder at which the edges are not joined and turning the protruding portion of the stamp over upon the other surface of the folder thereby causing it to be fixed to the last named surface.

7. The method of affixing stamps to mailing folders so as to join the free edges thereof, consisting in passing said folders through a means for affixing the stamp to one surface of a folder with a portion of said stamp protruding beyond the edge of the folder at which the edges of the different folds are not joined and turning the protruding portion of the stamp over upon the other surface of the folder by additional apparatus thereby causing it to be fixed to the last named surface.

8. The method of affixing stamps to mailing folders so as to join the free edges thereof consisting in passing said folders through a means for affixing the stamp to one surface of a folder midway between the ends of said folder with a portion of said stamp protruding beyond the edge of the folder at which the edges of the different folds are not joined and turning the protruding portion of the stamp over upon the other surface of the folder by additional

apparatus thereby causing it to be fixed to the last named surface.

9. In combination with means for affixing stamps to a folder with a portion of said stamp protruding beyond the edge thereof at which the edges of the different folds are not joined, of means for turning the protruding portion of said stamp over the edge of said folder upon the other surface of said folder and fixing it in its turned-over position.

10. The method of affixing stamps to mailing folders so as to seal the free edges thereof, consisting in affixing one end of the stamp to one surface of the folder with a portion of said stamp protruding beyond the edge of the folder at which the edges of the different folds are not joined, causing the folder to swing by gravity about a horizontal axis thereby causing the protruding portion of the stamp to be turned substantially at right angles to the affixed portion and affixing the remaining edge of the stamp to the surface of the folder opposite that to which the first end of the stamp was attached.

In testimony whereof, I sign this specification.

REED ADAMS.
